DESIGN FOR A SERVING UNIT

Malcolm W. Lowenstein, Baltimore, Md., assignor
of one-half to Samuel Silberstein, Baltimore,
Md.

Application September 3, 1941, Serial No. 103,145

Term of patent 7 years

To all whom it may concern:

Be it known that I, Malcolm W. Lowenstein, a citizen of the United States, residing in the city of Baltimore, State of Maryland, have invented a new, original, and ornamental Design for a Serving Unit, of which the following is a specification, reference being had to the accompanying drawing, forming part thereof.

In said drawing:

Fig. 1 is a view in side elevation of the serving unit, showing the dish and ladle elements comprising my design.

Fig. 2 is a top plan view thereof.

Fig. 3 is a fragmentary view in side elevation corresponding to Fig. 1, showing the opposite side of the dish element of the unit.

Fig. 4 is a bottom plan view of the dish element of the unit.

I claim:

The ornamental design for a serving unit, as shown and described.

MALCOLM W. LOWENSTEIN.
